(57) CLAIM

The ornamental design for a tent, as shown and described.

DESCRIPTION

FIG. 1 is a front elevation view of a tent showing my new design;

FIG. 2 is a right elevation view thereof;

FIG. 3 is a left elevation view thereof;

FIG. 4 is a top plan view thereof;

FIG. 5 is a bottom plan view thereof;

FIG. 6 is an isometric view thereof in a closed position;

FIG. 7 is a right isometric view thereof in an open position;

FIG. 8 is a left isometric view thereof in an open position; and,

FIG. 9 is an in-use isometric view.

The broken lines in FIG. 9 of the drawings depict a motorcycle as environmental subject matter only and form no part of the claimed design.
